Primary Examiner — Susan Bennett Hattan*Assistant Examiner* — Brett Miller(74) Attorney, Agent, or Firm — Faegre Baker Daniels LLP(57) CLAIM

We claim the ornamental design for the pool with a spa, as shown and described.

DESCRIPTION

FIG. 1 is a front perspective view of a pool with a spa of the present application;

FIG. 2 is a top view of the pool with a spa of FIG. 1; FIG. 3 is a bottom view of the pool with a spa of FIG. 1; FIG. 4 is a front view of the pool with a spa of FIG. 1; FIG. 5 is a rear view of the pool with a spa of FIG. 1; FIG. 6 is a side view of the pool with a spa of FIG. 1; and, FIG. 7 is another side view of the pool with a spa of FIG. 1. The broken lines in FIGS. 1-7 depict environmental structure and form no part of the claimed design.
